UNITED STATES PATENT OFFICE.

ANATOL M. JOSEPH, OF NEW YORK, N. Y.

DEVELOPING APPARATUS FOR PHOTOGRAPHIC FILMS.

Application filed August 24, 1926. Serial No. 131,169.

The object of the present invention is to provide a daylight developing apparatus for photographic films, characterized by the fact that the device is adapted to receive the 5 films from the film holder of a camera, such as a motion picture camera, and to wind in the film by rotation of a member of the receiving apparatus, a reverse rotation of said member serving to spread the film and 10 separate its convolutions so that the entire emulsified surface of the film may be exposed to the developing liquid.

A further characteristic of the invention is the provision and means whereby the 15 developing apparatus may be submerged in a developing bath so that the developing fluid may pass into the device through passages so formed as to bar the entrance of light. Thus the apparatus, after being submerged in one bath, may be removed therefrom and pass successfully to toning, fixing 20 and other baths or washes without removing the film. Further objects of the invention will hereinafter appear.

25 The invention will be understood by reference to the accompanying drawing, in which—

Figure 1 is an elevation of an embodiment of the invention, the vertical wall being 30 partially broken away, and

Figure 2 is a similar plan view;

Figure 3 is a sectional elevation of the device;

Figure 4 is a horizontal section on the 35 line 4—4, Figure 3, and

Figure 5 is a partial horizontal section on the line 5—5, Figure 3.

The embodiment of the invention illustrated in the drawing consists of a cylindrical casing 1 which is received on a base 40 member 2, the latter being provided with supporting legs 3 so as to maintain the bottom wall of the base member in raised position.

45 The base member 2 is formed with an axial aperture to receive the lower hub member 4^x of a drum 4. Hub member 4^x is provided with a depending threaded reduced end which receives a thumb-screw or nut 5. 50 It will be understood that the hub member 4^x will be so fitted within the aperture of

base member 2 as to bar the entrance of light.

Drum 4 is provided with an upwardly projecting hub member 4^{xx} adapted to be 55 received within the axial aperture of a cap plate 6. Both the base member and the cap plate are provided with shoulders indicated at *a* against which the edges of the cylindrical casing 1 bear.

60 Hub member 4^{xx} of the drum is provided with a threaded opening to receive a shouldered threaded stud 7, having at its upper end a thumb-piece 7^x. The shoulder 7^{xx} of the thumb-piece serves to hold in position 65 a knob 8, the lower face of which engages hub member 4^{xx} of drum 4 and extends over upon cap member 6. It will thus be seen that the thumb-nut 5 and knob 8 (with the shouldered screw stud 7) serve to maintain 70 the parts assembled and at the same time there will be provided sufficient clearance between the said two members and the adjacent surfaces of the cap plate and base member as to enable ready rotation of the 75 drum without substantial friction upon said base and cap members.

As shown in Figure 5, an opening *b* is 80 formed in the casing 1 to permit the passage of the film, indicated at 9. The opening is closed against the entry of light by two 85 pieces of soft rubber 10 which have meeting faces. In the figure I have indicated a fragment of a film box 11, having an outlet projection 12 adapted to project within opening *b*. The outlet projection 12 also passes into the opening of plate 13 on casing 1. The plate is secured by the screws 14, which screws also secure small plates 14^x 90 and serve to hold the soft rubber pieces 10 in position.

In order to start the operation of the device, stud-screw 7 is removed together with knob 8 whereupon cap 6 may be removed, exposing the interior of the device. The 95 film 9 then is passed into lateral *c* in drum 4 and is clamped in position by the rotation of a cam 15. The upper end of cam 15 is squared for a key and provided with a thumb-piece so as to be readily rotated. It 100 projects into an annular recess 4^x at the top of the drum.

When the end of the film to be treated is locked in position by cam 15, the cap member 6 and its associated parts are replaced, thus sealing the device against the entrance of light. Drum 4 is then rotated by hand or otherwise until all of the film to be treated is wound upon the drum and the outer end of the film passes into the drum. The drum is then given a reverse rotation which causes the outer free end of the film to meet the inner wall of the casing either by friction or by engagement with the plates 14* or other stops which may be provided. Thus said outer end of the film is held whilst the drum in its continued reverse rotation spaces the convolutions of the film to permit the entry of the treating liquid throughout the film surface.

The device is then placed in a container holding the liquid—which may be a developing solution, toning solution, washing bath, etc., in accordance with the desired treatment to be given. The film may be alternately wound upon drum 4 and then released by reverse rotation of the drum whilst the device is in the bath. This may be found desirable in order to agitate the liquid, and to insure thorough treatment of the film.

30 The liquid enters the casing through an opening or a plurality of openings 16 formed in the cap and base members 2 and 6. Each opening 16 is in connection with a horizontal passageway 17, which discharges into an annular channel 18 formed in cap and base members 2 and 6, at the outer edge thereof. The casing 1 serves as the outer wall for annular channel 18. The liquid flows along channel 18 until it meets 40 a horizontal passageway 19 permitting the liquid to flow inwardly. Passageway 19 is provided with outlets 20 leading to the interior of the casing adjacent the drum 4.

The base member 2 may be formed with 45 the same passageways as those provided in the cap member, and a further description thereof is unnecessary.

It will be understood that the passageways in both the cap and base members will 50 have non-reflecting surfaces. They may be coated with a black preparation which will absorb light. Thus light passing through the openings 16 may enter the horizontal passageway 17 but will not be reflected back 55 through the passageway 19 and into the casing 1.

Having described my invention what I claim and desire to secure by Letters Patent is as follows:—

60 1. In developing apparatus for strips of photographic films or the like, a casing, a drum adapted to rotate within the casing and means for conveying a liquid to the interior of the casing comprising reversely directed and spaced ducts, one of the ducts

having a communication with the interior of the casing, and the second duct communicating with the first duct and with the exterior of the casing.

2. In developing apparatus for strips of photographic films or the like, an annular casing, a drum adapted to rotate within the casing, a cap member for closing the casing and also serving as a bearing member for the drum, and a plurality of radial ducts 70 formed in the casing, each duct communicating with an annular channel, one duct communicating with the exterior of the casing and an adjacent duct communicating with the interior of the casing.

3. In developing apparatus for strips of photographic films or the like, an annular casing, a base member and a cap member, a drum rotatably held by the base and cap members, a light-tight aperture in the casing for the passage of the film, a slot in the drum, and clamping means for holding a film within said slot, and means for permitting the passage of liquid from the point exterior of the casing to a point interior thereof and comprising a duct formed in one of the cap and base members, said duct having a passageway leading exteriorly of the member, a duct within said member and having a passageway leading to the interior of the member, the two ducts communicating with each other in such manner that the liquid passes through one duct in a direction substantially opposite to its passage in the other duct.

4. In photographic apparatus, a developing device, comprising an annular casing, a drum, a base member closing the bottom of the casing and affording a bearing for the drum, a cap member closing the top of the casing and affording a second bearing for the drum, a plurality of radial ducts formed in one of said members, alternate ducts communicating with the interior of the casing and the remaining ducts communicating with the exterior of the casing, a passageway being formed in said member for intercommunication between the ducts.

5. A device constructed in accordance with claim 4, including means for holding the parts in assembled position, comprising a depending threaded extension on the drum, a nut carried by said extension, a knob disposed at the top of the drum and overhanging the cap member and a shouldered stud threaded in the drum axially thereof and serving to clamp the knob rigidly to the drum.

6. A device constructed in accordance with claim 4 in which the radial ducts are formed in both the cap member and the base member, and the base member is provided with a series of depending projections for supporting the device in such manner that liquid may enter the ducts from below.

7. In a device of the character described, a light-proof casing having a passageway for the admission of liquid, a drum within the casing, means whereby a photographic film or the like may be passed through the casing and clamped at the drum, and means whereby the drum may be rotated in reverse directions to first wind in the film and secondly to spread the convolutions of film to permit the action of the liquid on the 10 film surface.
- 5 In testimony whereof, I have signed my name to this specification.

ANATOL M. JOSEPHO.
